(57) CLAIM

The ornamental design for an overcap, as shown and described.

DESCRIPTION

FIG. 1 is a perspective view of the overcap showing an embodiment of the new design,

FIG. 2 is front elevation view of FIG. 1,

FIG. 3 is a rear elevation view of FIG. 1,

FIG. 4 is a right side elevation view of FIG. 1,

FIG. 5 is a left side elevation view of FIG. 1,

FIG. 6 is a top plan view of FIG. 1, and

FIG. 7 is a bottom plan view of FIG. 1;

FIG. 8 is a perspective view of the overcap showing an embodiment of the new design;

FIG. 9 is front elevation view of FIG. 8,

FIG. 10 is a rear elevation view of FIG. 8,

FIG. 11 is a right side elevation view of FIG. 8,

FIG. 12 is a left side elevation view of FIG. 8,

FIG. 13 is a top plan view of FIG. 8; and,

FIG. 14 is a bottom plan view of FIG. 8.
